UNITED STATES PATENT OFFICE.

FRANK P. PRENDERGAST, OF DAGUS MINES, PENNSYLVANIA.

SPARK-ARRESTER.

No. 820,599.

Specification of Letters Patent.

Patented May 15, 1906.

Application filed December 13, 1905. Serial No. 291,608.

To all whom it may concern:

Be it known that I, FRANK P. PRENDERGAST, a citizen of the United States, residing at Dagus Mines, in the county of Elk and State of Pennsylvania, have invented certain new and useful Improvements in Spark-Arresters, of which the following is a specification.

The object of my invention is to provide an improved construction of spark-arresters for locomotives.

For a full description of the invention and the merits thereof and also to acquire a knowledge of the details of construction of the means for effecting the result reference is to be had to the following description and accompanying drawings, in which—

Figure 1 is a vertical longitudinal section illustrating my invention. Fig. 2 is a horizontal section taken about on the line $x-x$ of Fig. 1.

Corresponding and like parts are referred to in the following description and indicated in both the views of the drawings by the same reference characters.

In the drawings the numeral 1 designates a dome-shaped spark-arrester which is designed to be secured in an elevated position above the top of the locomotive-stack 2 by means of rod-supports 3, secured to the upper edge of the said stack and to an inner annular rim 1^a of the spark-arrester 1.

4 designates the smoke-box.

From both sides of the spark-arrester 1 and between the annular inner rim thereof and the outer wall of said arrester there are secured two downwardly-extending pipes 5, the upper ends of which, where they leave the space formed by the two walls of the spark-arrester, are inwardly curved or sloped as shown at 5^a. Conducting-pipes 6 are secured at their upper ends by means of unions 7 to the lower ends of the pipes 5, and the said pipes 6 converge toward their lower ends and are secured by means of unions 7^a in the two branches of a three-way or Y coupling 8. The latter is secured at its lower end in a pipe 9, which leads through the smoke-box 4 and which is designed to discharge the sparks or cinders to the track-rails, if desired. The

pipe 9 is exteriorly screw-threaded at its upper end and is screwed into a plate 10, which is riveted to the smoke-box, as shown. The threaded end of the pipe 9 projects above the plate 10 and is screwed into the main branch of the three-way union 8, which latter is interiorly screw-threaded for that purpose. By this means a very secure and rigid construction is effected.

In the practical operation of the improved spark-arrester the sparks discharged from the stack 2 will be arrested by the dome-shaped wall of the part 1 and will be deflected thereby outwardly over the inner annular rim 1^a and into the pipes 5. The sparks will then readily slide down the sloping walls 5^a of the pipes 5 into the pipes 6 and thence into the pipe 9. It is to be understood that the pipes 6 may be located at any side of the stack 2.

Having thus described the invention, what is claimed as new is—

1. The combination with a smoke-stack, of a dome-shaped plate provided with an inner annular rim spaced from its outer rim and concentric therewith, supporting-rod secured at their lower ends to the upper edge of the stack, and at their upper ends to the said inner annular rim, whereby the outer rim of said plate will extend around or outside of the margin of said supporting-rods, conducting-pipes secured at their upper ends to the dome-shaped plate between the inner and outer rims thereof, and extending downwardly outside of the supporting-rods and to one side of the stack, and a pipe 9 to which the lower ends of the said conducting-pipes are connected, the said conducting-pipes being provided at their upper ends with sloping portions 5^a.

2. The combination with a smoke-stack and a smoke-box of a locomotive, of a dome-shaped plate secured in an elevated position over the upper edge of the stack and provided with an inner annular rim, downwardly-extending pipes 5 secured to said plate between the said inner rim and the outer wall thereof, conducting-pipes connected to the lower end of the first-named pipes, said conducting-pipes converging at their lower ends, 100

a plate secured to the smoke-box and internally screw-threaded, a pipe 9 inserted in said plate and secured therein and having a screw-threaded end projecting thereabove, 5 and a three-way coupling having a screw-threaded engagement with the projecting end of said pipe, the branches of said coupling being respectively connected to the lower

converging ends of the said conducting-pipes.

In testimony whereof I affix my signature in presence of two witnesses.
